DESIGN FOR A HEADLIGHT

Peder M. Knudsen, Katonah, N. Y.

Application February 15, 1941, Serial No. 99,022

Term of patent 14 years

To all whom it may concern:

Be it known that I, Peder M. Knudsen, a citizen of the United States of America, residing at Katonah, in the county of Westchester and State of New York, have invented a new, original, and ornamental Design for a Headlight, of which the following is a specification, reference being had to the accompanying drawing, forming a part thereof, wherein:

I claim:

The ornamental design for a headlight, as shown.

PEDER M. KNUDSEN.
